ABSTRACT OF THE DISCLOSURE

The surface of a candle made from stearin, paraffin wax or the like is decorated by covering the surface with a fat soluble dye mixed with a volatile solvent such as turpentine; and then heating the surface locally with a source of heat such as a flame so that the dye goes into the material of the candle, which is liquified at the surface, where it floats, while the volatile solvent is driven off. When the surface of the candle is hardened, it can then be polished.

FIELD OF INVENTION

The present invention relates to methods for decorating the surfaces of candles made from stearin, paraffin wax or similar material and to candles obtained by such methods.

BACKGROUND OF THE INVENTION

Methods are known including a series of proposals for the decoration of candles by which candle surfaces are provided with a color pattern by means of templates or the like, or whereby the surfaces are formed, for example, to have a resemblance to snow or ice.

SUMMARY OF INVENTION

An object of the invention is to provide an improved decorating method for treating the surfaces of candles, whereby individual artistic decorations are obtained.

This is achieved by applying to the surface of a candle preferably fat-soluble dyestuff mixed in turpentine or a similar volatile solvent and by then submitting the surface to a preferably localized heating from a source of heat, whereby the turpentine or the volatile solvent evaporates and the surface of the candle is brought to melting temperature, so that the dyestuff is mixed into the surface layer of the candle at the time that this layer is liquified. The candle is turned manually as well as moved in its longitudinal direction in relation to the source of heat so that the surface layer, into which the dyestuff is mixed, floats to form desired patterns in accordance with the relative movement of the candle and said source. The pattern thus provided is then allowed to harden and is finished by polishing.

The relative movement between the candle and the source of heat is preferably carried out manually, whereby the producer can provide individualized decorations on the surface of the candle. Besides the pattern of colors and shades, one can also produce artistically formed surfaces for such candles.

The heating of the surface of the candle by means of said source of heat is preferably carried out in localized fashion so that the producer continuously has a clear picture of how the pattern is formed and can easily control the same.

The source of heat can be a spirit flame or a similar source burning with a clear flame, whereby the surface of the candle is brought to melting temperature without being contaminated. If desired, however, a wick burner or the like can be used of the kind which forms carbon black. By holding the candle so near such a source of heat that carbon black is formed in the surface of the candle, dec-

2

orative areas or lines of carbon black particles can be obtained on the surface of the candle.

The application of dyestuff can be carried out by painting the same on the candle surface by means of a brush, or the dyestuff can be sprayed on the surface or applied by submersion of the candle in the same. The applying of the dyestuff can also be carried out in accordance with a special pattern, which later forms the basis for the formation of the final pattern obtained by the described heating and floating of the surface layer. In the mixture of the dyestuff and the turpentine or other soluble solvent, wax can be selected to obtain favorable floating and viscosity during the heating process. Between the application of the dyestuff dissolved in turpentine or other volatile solvent and the heating, the candle is preferably allowed to harden.

After the finished pattern is formed on the surface of the candle, it is finally allowed to harden and is then polished by means known per se.

BRIEF DESCRIPTION OF DRAWING

FIGS. 1(a) and 1(b) are respectively top and side views of a candle;

FIGS. 2(a) and 2(b) are respectively top and sides views of said candle with dyestuff applied thereto;

FIG. 3(a) is a top view of said candle showing how heat is applied thereto;

FIG. 3(b) is a side view of said candle illustrating dye disposition as a result of the heating; and

FIGS. 4(a) and 4(b) illustrate the polished candle.

DETAILED DESCRIPTION

FIGS. 1(a) and 1(b) respectively are top and side views of a candle to be decorated in accordance with the method of the invention. More particularly there is provided a candle 10 having a cylindrical side surface 12 with a top 14 and a bottom 16, the candle being conventionally provided with a wick 18.

FIGS. 2(a) and 2(b) illustrate that there has been applied, to the surface of the side 12, a mixture 20 consisting of a fat soluble dyestuff mixed in a volatile solvent such as turpentine.

In FIG. 3(a) is indicated a source of heat 22. This provides for localized heating of the side of the candle so that the wax surface melts and the dyestuff floats therein, the volatile solvent having been evaporated either by the heat source 22 or by simple evaporation prior to the application of heat.

Finally, the dyestuff floats in the surface as indicated at 24 in FIG. 3(b) and the surface is permitted to harden whereafter, as indicated in FIGS. 4(a) and 4(b), the candle is preferably polished by conventional means known per se.

Thus, it is seen that the invention provides for applying to the surface 12 of a candle 10 a preferably fat soluble dyestuff in turpentine or a similar volatile solvent and by then submitting the surface 12 to a preferably localized heating from a source of heat 22 whereby the turpentine or volatile solvent evaporates and the surface of the candle is brought to melting temperature so that the dyestuff is mixed into the surface of the candle while this surface is liquified.

The candle is preferably turned manually as well as moved manually in its longitudinal direction in relationship to the heat source 22 so that the surface layer into which the dyestuff is mixed floats to form a desired pattern in accordance with the relative movement of the candle and the source.

As noted above, the pattern is then permitted to harden and may then preferably be finished by polishing. The heating of the surface of the candle prior to the hardening of this surface is preferably carried out in localized

fashion and manually as aforesaid so that the candle producer continuously has a clear picture of how the pattern is formed and can easily control the same.

The heat source 22 can be a spirit flame or a similar source burning with a clear flame whereby the surface of the candle is brought to melting temperature without being contaminated. If desired, however, the heat source 22 can be a wick burner or the like which can be used to generate carbon black. In this case the candle is held close to the source of heat so that the carbon black is deposited on the surface of the candle so that decorative areas or lines of carbon black particles are obtained.

The application of the dyestuff can be carried out by painting the same on the candle surface by means of a brush or the dyestuff can be sprayed on the surface or alternatively the dyestuff can be applied by the submersion of the candle in the volatile solvents in which the dyestuff is mixed. The application of the dyestuff can also be effected in accordance with a special pattern which later forms the basis for the formation of the final pattern obtained by the localized heating and floating of the surface layer.

In the mixture of the dyestuff and the turpentine or other such solvent, wax can be employed particularly to obtain favorable floating and viscosity characteristics during the heating process.

Between the application of the dyestuff dissolved in the solvent and the heating, the candle can preferably be allowed to harden.

As to the dyes, there may be used any commercially available dye of the above noted kind and preferably aniline dyes.

What is claimed is:

1. A method for decorating a candle made of stearin, or paraffin wax comprising applying to the surface of the candle a dyestuff mixed in a volatile solvent for the candle, locally heating said surface of the candle from a heat source whereby the surface of the candle is liquefied and the dyestuff floats therein and the solvent is removed,

moving the candle longitudinally and rotationally during said heating respect to the heat source to form a pattern of the dyestuff on the surface of the candle, and then permitting the surface to harden.

- 5 2. A method as claimed in claim 1 comprising polishing the hardened surface.
3. A method as claimed in claim 1 wherein the dyestuff is fat soluble.
- 10 4. A method as claimed in claim 1 wherein the solvent is turpentine.
5. A method as claimed in claim 1 wherein the candle is manually rotated and moved longitudinally.
- 15 6. A method as claimed in claim 1 wherein the surface is heated by a heat source which is a source of carbon black which is deposited on the surface.
7. A method as claimed in claim 1 wherein the mixture of dyestuff and solvent is permitted to dry before the heating.
- 20 8. A method as claimed in claim 1, wherein the surface of the candle is heated by a heat source which does not contaminate the decoration produced by the color of the dyestuff.
